UNITED STATES PATENT OFFICE.

CHARLES B. ROBERTS, OF BERKELEY, CALIFORNIA.

HINGE.

1,401,734.

Specification of Letters Patent. Patented Dec. 27, 1921.

Application filed October 30, 1920. Serial No. 420,634.

To all whom it may concern:

Be it known that I, CHARLES B. ROBERTS, citizen of the United States, residing at the city of Berkeley, in the county of Alameda and State of California, have invented certain new and useful Improvements in Hinges, of which the following is a specification.

This invention relates to improvements 10 in hinges and has as its object the construction of a hinge in which the distance between the two leaves in their closed position may be adjusted.

In accomplishing this object, one of the 15 hinge leaves is made of the usual type, the other leaf being formed with an enlarged knuckle in which is held a bushing having an eccentric opening which opening holds the pivot pin. By rotating the bushing the position of the hole is changed, with reference to the faces of the hinge leaves and thus the pivot pin and the other knuckle are correspondingly moved.

The construction as herein illustrated differs in appearance but little from the usual hinge construction, is easily adjusted and effectively holds its position for any adjustment.

With these and other objects in view, my 30 invention consists in certain novel features of construction, combinations and arrangement of parts herein illustrated and more particularly pointed out in the appended claims.

35 Reference being had to the accompanying drawings forming a part of this specification:

Figure 1 is a view in elevation of my improved hinge.

40 Fig. 2 is a view in section through the sleeves showing the interior construction of the hinge.

Fig. 3 is a view in section on the line 3—3 Fig. 1.

45 Fig. 4 is a view similar to Fig. 3, but showing the parts in an adjusted position.

Referring to corresponding parts in the several views by the same numerals of reference: 1 and 2 denote the hinge leaves, the 50 former having knuckles 3 and 4 with an open space between. These knuckles contain axial openings 12 in which the pivot pin makes a close fit. The hinge leaf 2 is

formed with a knuckle 6 which fits between the knuckles 3 and 4 and has a somewhat larger diameter than the latter. Within knuckle 6 is a cylindrical bushing 7, having an eccentrically disposed axially extending hole 8 of the same diameter as the pivot pin. The back portion of the knuckle 6 has an 55 arcuate slot 9 through which extends a set screw 10. This set screw is in threaded engagement with the bushing 7 and by turning the screw inwardly the under surface of the head 11 contacts with the outer surface of 60 the knuckle and thus binds the bushing and holds it in a fixed position in the knuckle.

In use the hinge is attached to the door 15 and its jam 16 by means of screws 17. Then, if the door is not plumb or does not 70 line up with the door jam it may be brought into position by turning the bushing 7. If the bushing is turned in a counterclockwise direction, the two faces of the hinge leaves are brought closer together, while if it is 75 moved in a clockwise direction the hinge leaves are separated and the door correspondingly moved. When the correct adjustment has been made the screw is tightened to prevent further turning of the bushing and to 80 hold the adjustment of the door.

For the purpose of taking all shearing strains off the screw I provide a shoulder 14 at the bottom of hole 18 through the knuckle 6. Thus the weight of the door is 85 transmitted from knuckle 3 to bushing 7 and from the latter through shoulder 14 to knuckle 6 and thus to the fixed hinge leaf.

I claim as new and wish to cover by Letters Patent:

1. An adjustable hinge comprising hinge leaves, spaced knuckles having alining holes formed on one of said leaves, an enlarged knuckle on the other leaf adapted to fit between said spaced knuckles, a bushing adjustably held in said enlarged knuckle said bushing having a longitudinally extending eccentrically disposed hole, a shoulder on the lower end of said enlarged knuckle and a pivot pin extending through the holes in 100 said knuckles and the hole in said bushing.

2. An adjustable hinge comprising hinge leaves, spaced knuckles on one of said leaves having alining concentric holes, an enlarged knuckle on the other leaf adapted to fit between said spaced knuckles, a bushing revolu-

bly mounted in said enlarged knuckle, said bushing having an eccentrically disposed longitudinal hole, a shoulder on the lower end of said enlarged knuckle to prevent longitudinal displacement of said bushing, a screw engaging said bushing and extending through a slot in the enlarged knuckle, said

screw providing means for turning said bushing and holding it in adjusted position, and a pivot pin extending through the alining holes and through the hole in said bushing. ¹⁰

In testimony whereof I affix my signature.
CHARLES B. ROBERTS.
